UNITED STATES PATENT OFFICE.

DANIEL TROY HAILS, OF MONTGOMERY, ALABAMA.

DESIGN FOR A DOLL.

41,022.

Specification for Design.

Patented Nov. 29, 1910.

Application filed September 22, 1909. Serial No. 519,106. Term of patent 3½ years.

To all whom it may concern:

Be it known that I, DANIEL TROY HAILS, a citizen of the United States, residing at Montgomery, in the county of Montgomery and State of Alabama, have invented a new, original, and ornamental Design for Dolls, of which the following is a specification, reference being had to the accompanying drawing, forming part thereof.

The figure shown in Figure 1 is a front view and in Fig. 2 a back view of the doll.

What I claim is:

The ornamental design for a doll, as shown.

DANIEL TROY HAILS.
